MACHINE FOR MANUFACTURING
FLAT SPRINGS

Michel Souaya, 83 Rue Paul Vaillant Couturier,
Maisons-Alfort, Seine, France
Filed Oct. 15, 1962, Ser. No. 230,492
Claims priority, application France Nov. 4, 1961
1 Claim. (Cl. 140—89)

This invention relates to a machine for manufacturing flat springs.

Machines have been proposed for the manufacture of flat coil springs, starting from helical springs with abutting coils.

In these machines, the flat spring is manufactured by crushing or flattening successively the coils of the helical spring, in order to lay them. This crushing operation is effected through the intermediary of pinions and rollers between which the helical spring passes. However, because of this crushing, the flat springs thus manufactured have deep indentations reducing the mechanical resistance of the springs and also their elasticity.

Furthermore, in these manners of manufacturing flat springs, it is necessary to separate the abutting coils of the helical springs from each other before crushing or flattening them.

Finally, springs made by this method are not strictly flat and have a helical deformation which reduces or makes more difficult their utilization.

An object of the present invention is to obviate or mitigate these disadvantages.

The present invention is a method of manufacturing a flat spring from a helical spring, said method comprising feeding the helical spring in the direction of its axis and successively displacing the coil temporarily at the end thereof in a direction perpendicular to said axis.

The present invention is also a machine for manufacturing a flat spring from a helical spring, said machine comprising means for feeding the helical spring in the direction of its axis and means for successively displacing the coil temporarily at the end thereof in a direction perpendicular to said axis.

An embodiment of the invention will now be described, by way of example, with reference to the accompanying drawings, in which:

FIG. 1 is a diagrammatic perspective view of a machine according to the present invention;

FIG. 2 is a diagrammatic view of part of the machine, illustrating the device for displacing the end coil or spiral of the helical spring;

FIG. 3 shows the device in FIG. 2 in the working position;

FIG. 4 shows in front view the flat spring turned out by the machine of FIG. 1; and

FIG. 5 illustrates diagrammatically the manner of operation of the machine.

Referring now to the drawings, in obtaining a flat spring with coils or spirals by the method of the invention, firstly a helical spring 1 with abutting coils is disposed in a U-shaped slide 2.

The end coil 1₁ of this helical spring comes to bear against two rectilinear stops 3 and 4 set at a distance from each other and between which a vertically movable pusher or punch 5 is adapted to be accommodated. This punch 5 has at its lower end a notch 5₁ in which is adapted to be accommodated the coil which must be worked upon to obtain the flat spring 6.

The flat spring 6 is obtained by displacing successively the end coils 1₁ of the helical spring 1 perpendicularly to the axis of the helical spring. This displacement of the end coils 1₁ is effected by the punch or pusher 5 sliding in slides 18 which keep it strictly in a true path.

2

A spring 7 is hooked to the upper end of the punch 5 and is fixed on a shank 8₁ secured to a lug or tongue 8. This lug 8 is itself secured on a plate 9 supporting all the components of the machine. A bracket 10 fixed on a lever 11 articulated at 11₁ comes to bear on the upper end of the punch 5. At its other end this lever 11 is connected at 11₂ to a rod 12 whereof the end 12₁ is bent at a right angle and lodged in one of the holes 19₁ of a disc 19.

This disc 19 is mounted on the shaft of an electric motor, or any other device (not shown in the drawing) which enables it to be set in rotation. Due to this rotation, the disc 19 plays the part of an eccentric and as a consequence effects vertical displacement of the rod 12. This displacement of the rod 12 thus produces an oscillatory movement of the lever 11 and the bracket 10 about the pivot 11₁, which also effects a vertical reciprocating movement of the punch 5. This punch 5 returns in fact to its upper or raised position due to the presence of the spring 7 which draws it upwards against the lever 11.

The holes 19₁ in the disc 19 are spaced at different distances from the centre to permit movements of different amplitude of the punch or pusher 5.

The guiding of the helical spring 1 in the vicinity of the punch or pusher 5 is effected by the plate 9, by an upper plate 13, by a lateral rod 14 and by a lower plate 15.

The face 15₁ of the propping plate 15 is set in the same plane as the face 5₂ of the punch or pusher 5 so that the face 5₂ can slide against the face 15₁ to form the oval of the coil of the flat spring 6. Similarly, the rectilinear stops 3 and 4 arranged parallel to the axis of the helical spring have their ends 3₁ and 4₁ set at a distance from the plane of the faces 5₂ and 15₁ equal to the diameter of the wire from which the helical spring is made. In this way, only the end coil of the helical spring can be deformed by the punch or pusher 5 to form the flat spring. This punch or pusher 5 coacts with the end 16₁ of a stop 16 in order to form the coil of the flat spring.

The stem 16₂ of the stop 16 is curved so that the flat spring 6, on coming to bear with one of its faces on the said stem 16₂ and with its other face on a roller 17, is slightly curved which, as a result of the elasticity of this flat spring 6, effects the automatic advance of the spring 1 in the direction of the arrow F (FIG. 1). In this way, as soon as the end coil 1₁ of the spring 1 is displaced to form the spring 6, the following coil comes to bear against the ends 3₁ and 4₁ of the stops 3 and 4 which hold it in position.

50 The manner of operation of this machine is as follows:

The end coil 1₁ of the spring 1 bears constantly against the stops 3 and 4 therefore on account of the curvature of the flat spring 6 produced on the one hand by the stem 16₂ and on the other hand by the roller 17. However, this end coil 1₁ is slightly deformed initially, this deformation being caused by the work performed on the preceding coil.

When the punch or pusher 5 moves vertically from its top position downwards, the notch 5₁ comes to be engaged on the end coil of the spring 1 so as to cause it to descend perpendicularly to the axis of the said spring. The lower part of this coil then comes to abut on the end 16₁ of the stop 16 (FIGS. 3 and 5) the effect of which is to bring about the ovalization of the coil. The two dimensions of each coil are strictly constant since the gap left between the parts 16₁ and 5₁ is constant for each operation.

This end 16₁ of the stop 16 can be displaced vertically in order to be able to adjust the position of the end 16₁ according to the diameter of the spring 1 used and according to the ovality desired in the coil of the flat spring 6.

Similarly, the rectilinear stops 3 and 4 arranged parallel to the axis of the helical spring 1 can be displaced laterally, for instance by a screw device (not shown in the drawing) which enables them to be spaced at a greater or lesser distance from the face 15₁ of the stop 15 depending on the diameter of the wire forming the helical spring 1 on which work is to be done.

Furthermore, it should be noted that in adjusting the vertical position of the end 16₁ of the stop 16, the action of the punch or pusher 5 on the coils being shaped will be modified, which has the effect of curving the spring 6 in its own plane according to the direction of the arrows F₁ and F₂ in FIG. 4.

Similarly, the stops 13 and 14 could be displaceable in a known manner, to make it possible to match the position of these stops to the diameter of the helical spring used.

When the pusher or punch 5 returns to its upper position after having shaped a coil, another end coil comes into position against the stops 3 and 4. During this movement in the direction of the arrow F, the coil which has just been shaped by the pusher or punch 5 is released from the end 16₁ of the stop 16, in order now to bear against the bent part 16₂ of this stop 16. The curvature of the flat spring 6 also makes it possible, if desired, to bend the spring 6 permanently, perpendicularly to the plane of this spring, in the direction of the arrow F₃ (FIG. 2). For this purpose, the roller 17 is mounted on articulated arms 17₁ and 17₂ making it possible to bring

it more or less close to the stop 16, in order to emphasize to a greater or lesser degree the curvature of the spring 6 in the direction of the arrow F₃.

This machine makes it possible to obtain very regular flat coil springs, directly, starting from helical springs with abutting coils. Furthermore, these springs can be either rectilinear or curved in the desired direction, by modifying the position of the stops of the machine. Moreover, this machine can be used for helical springs of different diameter, and can displace the coils singly or in pairs or in greater numbers, with each reciprocating motion, according to the adjustment of the stops.

I claim:

In a machine for the manufacture of flat springs from a helical spring with abutting coils, adjustable guides and stops to guide the extreme coil of the helical spring under the point where the flat turns are formed, a punch above the extreme coil to be formed, means for effecting reciprocating rectilinear movement of the punch perpendicularly to the axis of the helical spring, a curved track for receiving the formed flat spring and a roller, the position of which can be varied, urging the said flat spring to bend round the said curved track to cause, by an elastic reaction, the automatic forward feed of the helical spring at each upward return stroke of the punch.
